[57] CLAIM

The ornamental design for a corn popping apparatus, substantially as shown and described.

DESCRIPTION

FIG. 1 is a perspective view of a corn popping apparatus showing our new design.

FIG. 2 is a front elevational view with the top lid shown in the closed position.

FIG. 3 is a left side elevational view thereof.

FIG. 4 is a right side elevational view thereof.

FIG. 5 is a top plan view thereof.
 The bottom surface of the corn popping apparatus is substantially planar and unornamented.

FIG. 1

FIG. 2
